UNITED STATES PATENT OFFICE.

ERIK S. HAGEN AND GEORGE B. TOWNSEND, OF CHICAGO, ILLINOIS, ASSIGNORS TO
NATIONAL PENNY SALES COMPANY, OF CHICAGO, ILLINOIS, A CORPORATION
OF ILLINOIS.

DESIGN FOR A VENDING-MACHINE CASE.

No. 39,158.

Specification for Design.

Patented Feb. 25, 1908.

Application filed January 10, 1908. Serial No. 410,274. Term of patent 7 years.

To all whom it may concern:

Be it known that we, ERIK S. HAGEN and GEORGE B. TOWNSEND, citizens of the United States, residing at Chicago, in the county of Cook and State of Illinois, have invented a new, original, and ornamental Design for Vending Machine Cases, of which the following is a specification, reference being had to the accompanying drawing, forming part thereof.

The figure is a front elevation showing our new design of a vending machine case.

We claim—

The ornamental design for a vending machine case, as shown.

ERIK S. HAGEN.

GEORGE B. TOWNSEND.
